UNITED STATES PATENT OFFICE.

ADOLPHUS A. SHIELDS, OF HUNTSVILLE, ALABAMA.

DESIGN FOR A SASH-LOCK.

SPECIFICATION forming part of Design No. 24,706, dated September 24, 1895.

Application filed July 27, 1895. Serial No. 557,391. Term of patent 14 years.

To all whom it may concern:

Be it known that I, ADOLPHUS A. SHIELDS, a citizen of the United States, residing at Huntsville, in the county of Madison and State of Alabama, have invented and produced a new and original Design for a Sash-Lock, of which the following is a specification, reference being had to the accompanying drawing, which represents a perspective view of the same.

The leading feature of my design is the pe-

culiar and ornamental form of the head *a* of the sash-lock, and the subsidiary or minor feature is the shank *b*.

What I claim is—

The design for a sash-lock, as shown and described.

ADOLPHUS A. SHIELDS.
